(57) **CLAIM**

The ornamental design for a single blade hair straightener, as shown and described.

DESCRIPTION

FIG. 1 is a perspective view taken from the top of a single blade hair straightener showing my design therefor;
FIG. 2 is a top plan view thereof;
FIG. 3 is a bottom plan view thereof;
FIG. 4 is a side elevational view thereof;
FIG. 5 is a front elevational view thereof; and,
FIG. 6 is a rear elevational view thereof.
